UNITED STATES PATENT OFFICE.

HENRY J. MUELLER, OF ST. JOSEPH, MISSOURI.

DESIGN FOR A CANDY LOZENGE.

51,628.

Specification for Design.

Patented Dec. 25, 1917.

Application filed September 19, 1917. Serial No. 192,214. Term of patent 14 years.

To all whom it may concern:

Be it known that I, HENRY J. MUELLER, citizen of the United States, residing at St. Joseph, in the county of Buchanan and State of Missouri, have invented a new, original, and ornamental Design for Candy Lozenges, as shown in the accompanying drawing.

Figure 1 is a plan view of the tablets, and Fig. 2 is a sectional side elevation.

I claim:

The ornamental design for a candy lozenge as shown.

HENRY J. MUELLER.

Witnesses:

J. STEWART FREUGER,
HERBERT E. REINKE.
